UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOCK KNIFE FOR KNOWLES HEADS.

Application filed May 25, 1927. Serial No. 194,174.

This invention relates to improvements in lock knives for pattern mechanisms of the kind set forth in Patent No. 134,992 and commonly known as the Knowles head.

In motions of this type there are employed a pair of oppositely rotating mutilated cylinder gears between which are mounted a plurality of vibrator levers each having a vibrator gear. By means of pattern mechanism the levers are raised and lowered so that the vibrator gears will be in mesh with one or the other of said mutilated cylinder gears. A connector extends from each vibrator gear to a harness jack and as the vibrator gears rotate the harness frames are either raised or lowered. It is necessary during the movement of the vibrator gears to hold the same in proper mesh with their actuating cylinders and this result has heretofore been accomplished by the use of a so-called lock knife which engages the inner end of the vibrator levers during the time that the harness frames are moving.

Heretofore this lock knife has been held on the upper end of a pivoted frame with its axis below the ends of the vibrator levers and a small cam rotating with one of the cylinders has effected back and forth motion of the knife by means of a small cam lever secured to the rocking frame.

I find that the lock knife is likely to be moved out of locking position by camming action at the point where the vibrator levers have contact with the lock knife due to the fact that said lock knife moves about a pivot. It is an important object of my present invention to provide a guide for the lock knife which will require the latter to have a straight line motion as distinguished from the previous pivotal motion, the effect of this construction being to overcome any tendency on the part of the lock knives to swing the lock knife around a center.

The several vibrator levers have their inner ends spaced by a comb and it is a more particular object of my invention to provide said comb with extensions having guides or trackways along which the lock knife is guided, motion being communicated to the lock knife by the usual cam and cam lever.

With these and other objects in view

which will appear as the description proceeds, my invention resides in the combination and arrangement of parts hereinafter described and set forth in the claims.

In the accompanying drawings wherein a convenient embodiment of my invention is set forth,

Fig. 1 is a front elevation of a Knowles head having my invention applied thereto,

Fig. 2 is a vertical section taken along line 2—2 of Fig. 1,

Fig. 3 is a top plan view of the structure shown in Fig. 2,

Fig. 4 is a vertical section on line 4—4 of Fig. 3 showing a portion of the lock knife device, and,

Fig. 5 is a top plan view showing the spring for the lock knife.

Referring more particularly to Fig. 1 it will be seen that I have provided upper and lower mutilated constantly rotating cylinder gears 10 and 11, respectively, which may be driven by any appropriate means such as that set forth in the aforesaid Knowles Patent No. 134,992. Said cylinders rotate in a head frame 12 which is secured to the arches 13 supported by the loom frame 14 and said head frame is provided with lateral extensions 15 between which extend a heel pin 16.

A plurality of vibrator levers 17 have their outer ends mounted on the heel pin and extend through a comb 18 shown particularly in Fig. 5. Said vibrator levers extend inwardly toward the center of the loom and each has pivotally mounted thereon a vibrator gear 19. A harness connector 20 is attached to each vibrator gear and has operative connection with a harness jack 21. A pin 22 on the head frame affords pivotal support for the harness jacks and the latter are rocked about said pin either to raise or lower the harness frames. By means of a pattern chain not shown herein but moving about an axis indicated at 23 said vibrator levers may be raised or lowered to produce any desired sequence of movements on the part of the harness frames or boxes.

The lower cylinder has secured thereto a cam 24 which cooperates with the cam lever 25 secured to a shaft 26. A pair of upstanding arms 27 are secured to said shaft 26 and afford means for moving the lock knife to be described hereinafter. The head

frame is provided with a cross girt 28 and there is secured to said girt an upstanding comb 29 having teeth which space the inner ends of the vibrator lever 17 as shown more particularly in Fig. 1. The matter thus far described with the exception of the particular form of arms 27 may be of common construction and for a more complete description of the same reference may be had to the aforesaid Knowles patent.

In carrying my invention into effect I provide a lock knife actuated by the arms 27 but not connected directly thereto and have further supplied guides to determine the line of movement of the lock knife. Accordingly, as shown more particularly in Figs. 1, 2 and 3, I provide each end of the comb frame 29 with an extension 40 which is provided with a horizontal bearing surface 41 and a shoulder 42 extending vertically therefrom. A cap 43 is secured to each extension 40 and is held in place by a bolt 44 and a toe 45. Said cap extends beyond the shoulder 42 and has the under surface thereof parallel with the bearing 41 to define a guide or trackway with the latter.

The lock knife 50 which if desired may be formed as used heretofore is fastened to a bar 51 having two pairs of spaced ears indicated at 52. Each pair of ears has pivotally connected thereto a link 53 the inner end of which is connected to the upper end of the corresponding arm 27. Said links and arms lie between the guideways for the lock knife and the latter projects beyond the ends of the bar 51 and into the guides or trackways. Said guides preferably extend in a horizontal direction although it may not be necessary in all adaptations of the invention to have the same extend in a truly horizontal plane.

As shown more clearly in Fig. 5 a resilient means is provided for holding the lock knife in holding position with respect to the vibrator levers, said resilient device including a bolt 60 secured to the comb 18 and having connected thereto a spring 61 the inner end of which is attached to an extension from one of the levers or arms 27. In this way the spring serves to hold the cam lever 25 against the cam 24 and also holds the lock knife 50 in holding position with respect to the vibrator levers.

In operation the cylinders rotate constantly with the result that said upstanding arms 27 reciprocate back and forth and by means of the links 53 provide reciprocating motion to the bar 51. This motion in turn is communicated to the lock knife and the latter is guided between the trackways so as to have holding engagement with the ends of the vibrator levers.

From the foregoing it will be seen that I have provided means for guiding the lock

knife so that the same will have substantially a straight line motion and will not tend to move about a pivot when strain in a vertical direction is exerted on said knife by the vibrator levers. It will further be seen that the comb which separates the inner ends of the vibrator levers is provided with guides or trackways which determine the direction of motion of the lock knife and that the means for imparting motion to the lock knife include the usual cam and cam lever.

Having thus described my invention it will be apparent that changes and modifications may be made therein by those skilled in the art without departing from the spirit and scope of the invention and I do not wish to be limited to the details herein disclosed, but what I claim is:

1. In a pattern mechanism including a constantly rotating cam to give a cam lever periodic oscillations, and having a pair of oppositely rotating mutilated cylinder gears between which lie a plurality of vibrator levers and vibrator gears for actuating harness jacks, a lock knife common to all the vibrator levers to have locking engagement therewith to restrain improper vertical motion of said vibrator levers, means providing substantially horizontal guides in which said lock knife moves, and connections between the cam lever and said lock knife to reciprocate same as the cam rotates.

2. In a pattern mechanism including a constantly rotating cam to give a cam lever periodic oscillations, and having a pair of oppositely rotating mutilated cylinder gears between which lie a plurality of vibrator levers and vibrator gears for actuating harness jacks, means defining spaced fixed guides extending in a direction substantially parallel to the vibrator levers, a lock knife common to all the vibrator levers and having the ends thereof extending into the guides, and connections between the cam lever and said lock knife to move the latter toward and from the vibrator levers as said cam rotates.

3. In a pattern mechanism including a constantly rotating cam to give a cam lever periodic oscillations, and having a pair of oppositely rotating mutilated cylinder gears between which lie a plurality of vibrator levers and vibrator gears for actuating harness jacks, means defining fixed spaced substantially horizontal guides, a lock knife common to all the vibrator levers and having the ends thereof received by the guides, a supporting bar to which the knife is attached, and means interposed between the bar and the cam lever to move said lock knife toward and from the vibrator levers as the cam rotates.

4. In a pattern mechanism including a constantly rotating cam to give a cam lever

periodic oscillations, and having a pair of oppositely rotating mutilated cylinder gears between which lie a plurality of vibrator levers and vibrator gears for actuating harness jacks, a lock knife common to all the vibrator levers, fixed spaced guides to receive the ends of the lock knife and guide the same so that said lock knife will have a right line motion toward and from the vibrator levers, a bar to which the lock knife is secured, links pivotally connected to the bar, and levers connected to the links and moved with said cam lever to reciprocate the lock knife in the guides as the cam gives periodic oscillations to the cam lever.

5. In a pattern mechanism including a constantly rotating cam to give a cam lever periodic oscillations, and having a pair of oppositely rotating mutilated cylinder gears between which lie a plurality of vibrator levers and vibrator gears for actuating harness jacks, a comb to space the ends of the vibrator levers, means defining a pair of spaced lower bearings rigid with the comb, a pair of caps fixed with respect to the comb and cooperating with said bearing surfaces to define a pair of spaced fixed guideways, a lock knife common to all the vibrator levers and having the ends thereof guided between the bearing surfaces and the caps, and means to reciprocate said knife in the guides toward and from the vibrator levers as the cam oscillates the cam lever.

6. In a pattern mechanism including a constantly rotating cam to give a cam lever periodic oscillations, and having a pair of oppositely rotating mutilated cylinder gears between which lie a plurality of vibrator levers and vibrator gears for actuating harness jacks, a comb to space the inner ends of the vibrator levers, means defining a pair of spaced lower bearings rigid with the comb, a pair of caps fixed with respect to the comb and cooperating with said bearing surfaces to define a pair of spaced fixed guideways, a lock knife common to all the vibrator levers and having the ends thereof guided between the bearing surfaces and the caps, and means to reciprocate said knife in the guides toward and from the vibrator levers as the cam oscillates the cam lever.

7. A comb for separating the ends of a plurality of vibrator levers forming part of a pattern mechanism including actuator cylinders and vibrator gears mounted on the vibrator levers, said comb being formed of a plurality of vibrator lever separating teeth and said comb also being formed with a pair of lock knife guides extending in a direction toward and from the separating teeth.

In testimony whereof I have hereunto affixed my signature.

WILLIAM M. WATTIE.
